CLAMPING DEVICE

Manuel Lucas, New York, N. Y.

Application November 24, 1937, Serial No. 176,233

4 Claims. (Cl. 223—110)

This invention relates to a clamping device and more specifically to a work-holding, clamping device.

In general, it is an object of the invention to provide a device of the character described, which will efficiently perform the purposes for which it is intended, which is simple and economical of construction, which can be expeditiously, conveniently and safely manipulated, and which can be readily manufactured and assembled.

Another object of the invention is to provide a clamping device which may be conveniently positioned for assembling the work and may be otherwise and conveniently positioned for presenting the work to an operative for further operations to be performed thereon; to provide such a device wherein elements used during the assemblage of the work upon the device are removable from the scene of operations to be performed after the work has been finally and fixedly clamped in position; and to provide such a device which is usable at once by an unskilled operative.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention, reference should be had to the following detailed description, taken in connection with the accompanying drawings, in which:

Figure 1 is a perspective view of a device embodying one form of the invention;

Fig. 2 is a sectional view, in elevation, of the device shown in Fig. 1, in closed position but without the main supporting frame;

Fig. 3 is a sectional view similar to Fig. 2, on a smaller scale and with a part thereof pivoted into removed position;

Fig. 4 is a perspective view of the clamping element shown in Fig. 2;

Fig. 5 is a plan view of a portion of the device shown in Fig. 1, the aligning element not being shown;

Fig. 6 is a perspective view of one pivotable, principal, supporting element of the main frame;

Fig. 7 is an enlarged view of a detail of the device shown in Fig. 1; and

Fig. 8 is a modified form of an element of the device shown in Figs. 1-7.

The clamping device of the present invention

is usable for clamping operations of various kinds in connection with various materials. It is particularly useful in the manufacture of neckties. The several parts of the machine will be described with that type of assembling in mind.

Specifically, there is a horizontal table on which is laid cloth which is to be sewn into a tie. Clamps hold the folded cloth or material in place. The insert or lining for the tie is placed on the clamped cloth. A covering plate swings down and binds the cloth and insert between itself and the table. The clamps and guides for the insert are then released and swung out of the way, leaving the edges of the material and part of the insert extending out from between the table and the covering plate which latter are then swung together into upright position so that the said edges and extending insert are positioned along the top of the machine where they are exposedly and conveniently presented to an operative for being sewed together. Thereafter, upon being removed from the machine, the tie is turned inside out, carrying its lining into the inside thereof. It may then be ironed so that the edges are in the position of a seam along the back of the tie and the lining is fixedly attached on the inside of the tie along the seam.

The parts of the device just mentioned and to be described in detail below are so simple in operation that they may be manipulated by an unskilled hand, who may sew by hand the exposed edges referred to. Neckties which are sewn by hand are known to tie better and to hold their shape better than those which are machine-sewn. As a result, hand-made ties of cheap material sell for more than machine-made ties of less expensive material, independent of the relative cost of machine and hand labor. Hand labor is costly, however, because there have not been devices suitable to cut down the time of the hand labor and because of the time required to train apprentices. Such training time may extend into months and this is a field where the labor turnover is very large. The utility and advantage of the present machine is obvious. A beginner may operate it after a few minutes and it presents the work to the operator in such a convenient position that even a trained sewer may perform the sewing steps in much shorter time than would be otherwise possible.

In the drawings, 10 denotes a standard or frame which holds the device proper. There are means for presenting edges of the tie material along an exposed line. These may take the form of a horizontal table or plate 12 having an edge 14. 55

The material for the tie is folded onto itself with two edges extending out over the edge 14. Means are provided to hold or clamp the tie material in place while the tie lining is being placed on the tie. There is a support for the clamping means. This last may be a ledge 16 extending away from edge 14 and generally in the plane of table 12. The edges of the tie material extend over onto ledge 16. Clamping means 18 are attached to the upper surface of ledge 16 as by bolts 20. The clamping means bind or fix the edges of the tie material against ledge 16 by means of the clamping tongues 22 which are fixed to, and pass through, an opening in upright springs 24 which hold the tongues 22 down against the material of the tie. The other ends of the tongues 22 may be used as handles 26. When the handles are depressed, tongues 22 are raised against the action of springs 24. The springs 24, with the attached tongues 22, may be pivotable around the bolts 20, respectively (see Figs. 2 and 5).

The ledge 16 also acts as a support for an element 28. The latter extends along ledge 16 above clamps 18. It may be sloped downwardly toward plate 12. It includes, as an integral part of itself or as a separate element, an upright 30 which stands on ledge 16 and forms a wall along which the edges of the tie may lie. Openings 32 in the upright wall permit the tongues 22 to extend through that wall to bear down upon the tie material. These openings may be of such extent that the tongues 22 may be pivoted about their respective bolts without contacting wall 30. Means may be provided for exactly positioning the regular or irregular periphery of the tie lining while the latter lies on top of element 28. Such means may be of the nature of a template 29, or one part of the surface of element 28 may be raised with respect to another. By means of this aligning element 29, a tie lining or insert is properly positioned so that it extends across the edges of the tie on ledge 16 and thus lies above both element 28 and plate 12.

An upper plate 34 is adapted to be brought down against the tie material and the tie lining in any suitable fashion. This plate or any equivalent means acts to bind the lining against the edges of the tie on plate 12. As shown, upper plate 34 is pivoted to the plate 12 along an edge of plate 12 parallel to edge 14. Plate 34 may be somewhat shorter lengthwise than plate 12.

Means are provided for removing the ledge 16 and the clamps 18 and aligning element 28, which are attached to ledge 16. It will be seen that once the upper plate 34 is in operation, the parts 16, 18 and 28 are no longer needed. Ledge 16 may be movable about a pivot 36 which is attached to the underside of plate 12. Suitable latch means 38 may coact with an aperture 40 on the lower side of plate 12. When the latch means are released, supporting ledge 16 is free to be pivoted away from edge 14.

The operation having begun with the plate 12 horizontal, the edges of the tie and part of the lining extend out, horizontally exposed, from between the plates after the ledge has been swung down. There are means which permit the two plates to be swung together as a unit from the horizontal position to a vertical position. These are shown in Fig. 6. An angle iron 42, having an upright arm 44 and a horizontal arm 46, is fixedly attached to each upright post 48 of frame 10. In the angle of the angle arm, there is a U-shaped element 50 pivoted on pivot 52 attached to post

48. The U-shaped element may be moved into horizontal or upright position, the vertical arm 44 holding the U-shaped element from swinging past upright position. A spring 54 on element 50 may releasably grip the upright arm 44. The end edges of the plate 12 sit in between the branches of the U-shaped element 50. The plate 12, therefore, is movable from the horizontal into the vertical along with element 50. Plate 12 carries plate 34 with it. When these plates, with the tie and insert clamped between them, are moved to the vertical position, the tie edges and insert are exposed along the top of the device along a line where they may be easily sewn together by hand by an operator. The plates 12 and 34 may then be lifted up out of the U-shaped element 50. They, or other similar plates, may be put back into element 50.

Spring controlled latch means 56 may be positioned along the free edge of plate 34 and adapted to coact with elements on the lower plate 12, such as openings 58. In case the aligning element 28 is not large enough to cover the clamping means 18, an extra extension 60 may be pivotally attached to element 28. The extension 60 acts as a guard to prevent thread, which is being used to sew the tie, from catching onto clamps 18.

Clamps 18 may extend farther than is shown in Fig. 5 and may reach over onto platform 12, in which case portions of the free edge of upper plate 34 may be removed so that the clamps 18 may be pulled away from plate 12 after upper plate 34 has been fixed in position.

There may be provided means for further assuring the relative fixity of the tie and insert materials between the upper and lower plates. For example, as is shown in Fig. 8, sharp teeth 62, integral with or attached to upper plate 34 along the free edge thereof, may extend through the tie and insert material and into cavities 64 in lower plate 12.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and useful and desire to secure by Letters Patent is:

1. In a clamping device of the character described, the combination comprising a platform 60 having a surface, a second platform having a surface, said surfaces being positioned so that neck-tie material may extend from one surface onto the other, a plurality of releasable clamps each associated with said second platform and positioned to be available to clamp two edges of folded neck-tie material, which is lying on said two surfaces, each against the other and against said second surface, a clamping plate movable to a position close to the first-mentioned platform whereby such folded material and a lining thereon and extending beyond said edges may be clamped between said plate and the first-mentioned platform, said clamping plate and said clamps being free to be operated together and 75

- also independently of the position of each other, whereby said clamping plate and the first-mentioned platform continue to hold folded tie material and lining material between them after said releasable clamps have been released from the folded material, a plate positioned to receive thereon that portion of a lining extending beyond the toe material edges and to keep that lining and said clamps spaced whereby said 5 clamps may be released after said clamping plate has clamped the lining against the tie material, the surface of each of said platforms and said clamping plate being at least as long as a neck-tie.
- 10 2. In a clamping device of the character described, the combination comprising a platform having a surface, a second platform having a surface, said surfaces being positioned so that neck-tie material may extend from one surface onto the other, a releasable clamp associated with said second platform and positioned to be available to clamp against each other and against said second surface two edges of folded neck-tie material which is lying on said two surfaces, a 15 clamping plate movable to a position close to the first-mentioned platform whereby such folded material and a lining thereon and extending beyond said edges may be clamped between said plate and the first-mentioned platform, said 20 clamping plate and said clamp being free to be operated together and also independently of the position of the other, whereby said clamping plate and the first-mentioned platform continue to hold folded tie material and lining material 25 between them after said releasable clamp has been released from the folded material, means for releasing said clamp, and means for removing said second platform from said tie material whereby the edges of the tie material and the lining clamped thereto are exposed for sewing, the surfaces of each of said platforms and said clamping plate being at least as long as a neck-tie.
- 25 3. In a clamping device of the character described, the combination comprising a platform having a surface, a second platform having a surface, said surfaces being positioned so that neck-tie material may extend from one surface onto the other, a releasable clamp associated 30 with said second platform and positioned to be available to clamp against each other and against said second surface two edges of folded neck-tie material which is lying on said two surfaces, and a clamping plate movable to a position close 35 to the first-named platform whereby such folded material and a lining thereon and extending beyond said edges may be clamped between said plate and the first-mentioned platform, said 40 clamping plate and said clamp being free to be operated together and also independently of the position of the other, whereby said clamping plate and the first-mentioned platform continue to hold folded tie material and lining material 45 between them after said releasable clamp has been released from the folded material, the surfaces of each of said platforms and said clamping plate being at least as long as a neck-tie.

MANUEL LUCAS. 50
